WITNESS:

BY *Victor J. Evans*
ATTORNEY

UNITED STATES PATENT OFFICE.

BENJAMIN A. REXFORD, OF ALTON, ILLINOIS.

TRAFFIC SIGNAL.

Application filed January 30, 1922. Serial No. 532,788.

To all whom it may concern:

Be it known that I, BENJAMIN A. REXFORD, a citizen of the United States, residing at Alton, in the county of Madison and State of Illinois, have invented new and useful Improvements in Traffic Signals, of which the following is a specification.

This invention comprehends the provision of a traffic signal, which embodies amongst other features a post or upright adapted to be arranged in the center of a street intersection, and equipped with means indicating the directions of north, east, south and west, and also means for warning the drivers of vehicles relative to the speed of the latter.

One of the chief characteristics of the invention resides in providing the post or upright with a spherical body having a mirror surface so that the driver of any vehicle may readily see in the spherical body the approach of any traffic from any direction.

In carrying out the invention I provide the spherical body with a shade or covering to prevent the rays of sunlight from being reflected into the eyes of the drivers of the various vehicles which approach the intersection, and also support upon this shade or covering a lamp adapted to be illuminated at night time so that the signal can be readily seen.

The nature and advantages of the invention will be better understood when the following detail description is read in connection with the accompanying drawings, the invention residing in the construction, combination and arrangement of parts as claimed.

In the drawings forming part of this application, like numerals of reference indicate similar parts in the several views, and wherein:

Figure 1 is a view in elevation of the traffic signal constructed in accordance with the present invention.

Figure 2 is a sectional view taken on line 2—2 of Figure 1.

Figure 3 is a top plan view.

Referring to the drawing in detail, 10 indicates the post or other suitable standard which is adapted to be arranged at the cen-

ter of street intersections, and which standard may be constructed from any suitable material and also vary in size and configuration without departing from the spirit of the invention. Supported upon the standard 10 is a spherical body 11 having a mirror surface, so that the driver of a vehicle approaching the crossing or street intersection, can readily see in the spherical body the approach of any other traffic from any other direction. For the purpose of preventing this spherical body from reflecting the sun light in the eyes of the drivers of the various vehicles which approach the intersections, I arranged upon the spherical body a shade or covering 12 which may be constructed from any suitable material and of the proper dimensions for the purpose intended. The shade may also be secured or supported upon the spherical body in any suitable manner. Arranged immediately beneath the spherical body 11 and projecting from the standard 10 is a plurality of arms 13 which support the respective letters N, E, S and W which indicate the directions of north, east, south and west. Suspended from these arms are signs 14 each of which has suitably arranged thereon the word "Slow", thus warning the drivers of vehicles approaching the intersection to slow down in speed. The signal in its entirety is not only particularly useful in the respects enumerated, but it also presents a very ornamental and pleasing appearance to the eye.

In order that the signal may be readily seen at night time, I arrange upon the shade or covering 12 of the spherical body 11, a lamp 16 which may be an electric lamp or a lamp of any other character.

While it is believed that from the foregoing description the nature and advantages of the invention will be readily apparent, I desire to have it understood that I do not limit myself to what is herein shown and described, and that such changes may be resorted to when desired as fall within the scope of what is claimed.

What I claim is:

A device of the character described comprising a post adapted to be arranged at the

center of street intersections, said post having a reduced upper extremity defining a shoulder, a spherical post of hollow formation having a mirrored surface, said body 5 having diametrically opposed openings to receive the reduced end of said post, whereby said post reposes upon the said shoulder,

and a disk centrally supported on said post and of a diameter greater than the diameter of said spherical post to project beyond the 10 sides thereof, said disk constituting a shade for the purpose specified.

In testimony whereof I affix my signature.
BENJAMIN A. REXFORD.
